UNITED STATES PATENT OFFICE.

HARRY A. LEWIS, OF NORRISTOWN, ASSIGNOR OF NINE-TWENTIETHS TO
JAMES C. YERKES, OF READING, PENNSYLVANIA.

FUSE-HOLDER AND LIGHTNING-ARRESTER.

SPECIFICATION forming part of Letters Patent No. 554,130, dated February 4, 1896.

Application filed January 17, 1895. Serial No. 535,244. (No model.)

To all whom it may concern:

Be it known that I, HARRY A. LEWIS, of Norristown, in the county of Montgomery and State of Pennsylvania, have invented a 5 new and Improved Fuse-Holder and Lightning-Arrester, of which the following is a full, clear, and exact description.

My invention relates to improvements in that class of devices which are adapted for 10 use as fuse-holders and lightning-arresters, and which are adapted to automatically cut out the line of an electric circuit in case the current is excessively increased.

The object of my invention is to produce a 15 very simple contrivance of this kind which employs a fuse or fusible wire to form a part of the line, this wire being adapted to be burned out in case the current is excessively increased; also to provide means for easily 20 inserting and removing the fuse-block, to provide an automatic device for grounding the excessive current, and in general to produce a device which may be inserted in any electric circuit and will effectually prevent 25 instruments of various kinds from being burned out and ruined.

To these ends my invention consists of certain features of construction and combinations of parts, which will be hereinafter 30 described and claimed.

Reference is to be had to the accompanying drawings, forming a part of this specification, in which similar figures and letters of reference indicate corresponding parts in all the 35 views.

Figure 1 is a side elevation of the apparatus embodying my invention. Fig. 2 is a plan view of the same, and Fig. 3 is a longitudinal section on the line 3 3 of Fig. 2.

40 The apparatus is provided with a suitable base-board 10, at one end of which is an ordinary binding-post 11 to receive the line-wire A, and this binding-post also fastens to the block an angular grounding-plate 12, one arm 45 of which is fastened beneath the binding-post while the other extends upward parallel therewith, and opposite the grounding-plate and secured to the block is a second binding-post 13, which is adapted to receive a ground-wire B, this being fastened by a thumb-screw 50 14, and which also carries a contact-pin 15,

which is fastened by a thumb-screw 16 and which may be placed in contact with or slightly out of contact with the grounding-plate and fastened there.

55 Connected with the binding-post 11 is a wire C which is insulated and is wound upon an insulating-core 17 to form a choking-coil 18, so that when the current is suddenly increased the resistance will deflect a greater 60 part of the current through the ground-plate 12, the pin 15, the binding-post 13, and the wire B to the ground.

The wires C, after passing from the coil 18, connect with a binding-post 19 on the base-block 10, and this binding-post has an ordinary groove 20 adapted to receive the forked end 21 of a conducting-plate 22, which is fastened to one end of the insulating fuse-block 23, and the conducting-plate is also secured 70 to a binding-post 24, which is fastened to the fuse-block and which carries a U-shaped spring 25, having one end fastened beneath the binding-post and the other free end entering a slot 26 made transversely in the binding-post, this free end of the spring being adapted to clamp without cutting one end of the fusible wire D, the spring being clamped to the wire by a thumb-screw 27. The other end of the fusible wire D is fastened in a slot 80 26 of a binding-post 24^a, which is exactly like the binding-post 24 and which is fastened to the opposite end of the fuse-block 23, the second binding-post carrying a spring 25^a like the spring 25 just described, and the second 85 post has also a thumb-screw 27 to fasten the spring upon the wire D. This fusible wire, before being used, is insulated by dipping it into a solution of paraffine and sweet oil which, on cooling, forms a coating over the wire, the 90 oil serving to render the paraffine pliable and the coating protects the wire from atmospheric influences.

The binding-post 24^a has at one side of it a swinging lever 29 which is fulcrumed, as 95 shown at 30, and which has a bent free end 28 which extends beneath the fusible wire D, and a spring 30^a presses upward on the lever 29, so that when the fusible wire is melted or nearly melted by a heavy current the tension 100 of the spring causes the lever to carry the wire upward and swing it out of the line, thus

completely cutting out the line and saving any instruments which may be in connection therewith.

Beneath the binding-post 24^a is held one end 31 of a flat spring-lever 32 which, at its upper end, terminates in an insulating-handle 33, and in the lever 32 is a hole 34 which is adapted to receive a contact and locking pin 35 which is held in a binding-post 36 on the block 10, this binding-post being adapted to receive the line-wire A' which is fastened by a thumb-screw 38, while the pin 35, before mentioned, is fastened by a thumb-screw 37 and can be adjusted in and out if desired. By pressing forward on the lever 32 it may be sprung out of engagement with the pin 35 and the fuse-block lifted from the base-block 10, while by placing the forked conducting-plate 22 in engagement with the binding-post 19 and then swinging the lever 32 into place, so as to permit the pin 35 to enter the hole 34, the fuse-block is locked in position. The lever 32 therefore forms a catch acting in conjunction with the pin 35 to hold the fuse-block in position and at the same time effect the electrical connection.

Under normal conditions the current enters the wire A, passes through the binding-post 11, the wire C, the binding-post 19, the conducting-plate 22, the binding-post 24, the fusible wire D, the binding-post 24^a, the lever 32, the pin 35, the binding-post 36 and out through the wire A'. If, however, the current becomes dangerously strong, the action of the coil 18 causes a part of the current to be deflected through the plate 12, contact-pin 15, binding-post 13 and wire B to the ground without burning out the wire D, and if the current is still further increased the wire D is melted and the lever 39 lifts the melted wire out of the line and completely cuts out the current from the wire A'.

Having thus described my invention, I claim as new and desire to secure by Letters Patent—

1. A binding-post provided with a slot and a spring-clamp having one member station-

ary relatively to the post, and a movable spring member extending into the slot of the post, substantially as described.

2. The combination of the two binding-posts forming terminals of the line-circuit, the fuse-block, a conducting-coupling to connect the fuse-block to one of the binding-posts, the conducting-catch to connect the other end of the fuse-block to the second binding-post, the binding-posts on the fuse-block connecting with the said catch and the coupling respectively and adapted to receive a fusible wire, and the spring-lever on the fuse-block to engage the said wire, substantially as described.

3. A binding-post provided with a slot and a spring-clamp consisting of a substantially U-shaped plate one end member of which is held in the said slot, substantially as described.

4. A binding-post provided with a slot and a spring-clamp consisting of a plate having a stationary member engaging the lower surface of the post, and a movable spring member extending into the slot of the post, substantially as described.

5. The combination, with the two binding-posts forming terminals of the line-circuit, of the fuse-block, a conducting-coupling to connect the fuse-block to one of the binding-posts, the perforated spring-lever and connecting-pin, to connect the opposite end of the fuse-block to the second binding-post, the binding-posts on the fuse-block connecting with the coupling device, and the spring-lever and the fusible wire uniting the binding-posts on the fuse-block, substantially as described.

6. The combination, of the two slotted binding-posts, the spring-clamping devices held in the slots of the post, and the fusible wire connecting the posts, substantially as described.

HARRY A. LEWIS.
